UNITED STATES PATENT OFFICE.

CARL E. SPAULDING, OF LOWELL, MASSACHUSETTS.

TENSION-PULLEY-SUPPORTING BRACKET.

1,136,626.

Specification of Letters Patent. Patented Apr. 20, 1915.

Application filed November 16, 1907. Serial No. 402,400.

To all whom it may concern:

Be it known that I, CARL E. SPAULDING, a citizen of the United States, residing at Lowell, in the county of Middlesex, State of Massachusetts, have invented certain new and useful Improvements in Tension-Pulley-Supporting Brackets, of which the following is a specification, reference being had therein to the accompanying drawings.

The invention has relation to the means of supporting tension and guide-pulleys, and the like, such as are employed with the spindle-driving bands or tapes of spinning machines, twisting frames, and in other like connections.

An embodiment of the invention is illustrated in the drawings, in which latter,—

Figure 1 shows in side elevation a tension-pulley and a bracket or support therefor constructed for application to a spinning-frame, twisting frame, or the like. Fig. 2 is an elevation looking from the right-hand side in Fig. 1. Fig. 3 shows an opposite side elevation of the parts which are shown in Fig. 1. Fig. 4 is an elevation looking from the right-hand side in Fig. 3. Fig. 5, Sheet 2, is a view in transverse section on line 5, 5, of Fig. 3. Fig. 6, Sheet 2, is a side elevation of the principal member of the forked bracket or support, shown separately. Fig. 7 is an elevation looking from the left-hand side in Fig. 6. Fig. 8 is a side elevation of the second member or arm of the said bracket or support. Fig. 9 is an elevation looking from the right-hand side in Fig. 8. Figs. 10 and 11 are views showing one of the bearing-blocks detached.

Having reference to the drawings,—at 1, Figs. 1 to 5, is a tension-pulley of the kind commonly in use in connection with the flat spindle-driving bands or tapes that are employed in some varieties of spinning-frames, twisting-frames, etc.; 2^a, 2^b, are opposite arms of the bracket in which the said tension-pulley is mounted, the said arms receiving the tension-pulley between them. In practice, the bracket is attached to a suitable support (not shown) in the spinning-frame or other machine in which the device is employed, by means of a screw or bolt passed through the hole 2^c in the outer or upper end of the arm 2^a of the bracket. The tension-pulley is provided, as usual, with journals 1^a, 1^b, Fig. 5, projecting from opposite sides of the same, and the arms of the brackets are furnished with bearing-blocks

3, 3, each of which is formed with the hole or socket 3^a, Figs. 5, 10 and 11, which receives one of the said journals. By means of said journals and bearings the tension-pulley is supported in the bracket. The hole or socket 3^a in each bearing-block is cylindrical, and extends longitudinally of the block. Each block is contained in a pocket 2^d, Figs. 7, 8 and 9, in the corresponding arm of the bracket, the opening by which the block is introduced into and removed from the pocket being at the side of the arm which is next the tension-pulley.

In order to restrain the tension-pulley from side-play, the exposed inner ends of the two bearing-blocks are arranged to engage with shoulders 1^b, 1^b, Fig. 5, at opposite sides of the body of the tension-pulley, such shoulders being located at the inner ends of the journals 1^a, 1^b. The said shoulders are constituted in the present instance by the outer sides of the nuts 1^c, 1^c, that are screwed on the threaded middle portion of the central shaft of the tension-pulley. The said nuts hold the body of the tension-pulley in place on the shaft, washers 1^d, 1^d, Fig. 5, being interposed between the nuts and the opposite sides of the body. The bearing-blocks, which in some cases in practice may be of any suitable material, character, and construction, preferably are made of wood, saturated with oil, although they may be saturated or otherwise charged with other suitable lubricant. Beyond the periphery of the tension-pulley, the arms 2^a, 2^b, bend toward each other, and portions thereof overlap each other, as shown in Figs. 1 to 4, the overlapping portions 2^e, 2^f, being halved to reduce the combined thickness, as shown clearly by the detail views, Figs. 6 to 9 of Sheet 2, and being connected together by means of a rivet 4, Figs. 1 to 4, serving as a pivot. The stem of the said rivet passes through holes 2^g, 2^h, in the said overlapping portions of the arms, its spread or upset ends engaging with the outer faces of the arms. The rivet holds the meeting faces of the overlapping portions of the arms in contact with each other. It constitutes a pivotal connection for the two arms, providing for swinging movements of one thereof with relation to the other to carry the free extremities of the arms transversely toward and from each other. The extent of the opening movement is limited through contact of the outer side of the arm 2^b with the raised stop

at 2¹, (Fig. 7) on the arm 2^a, and that of the closing movement is limited by contact of shoulder 2^k, Figs. 8 and 9, of the arm 2^b with the shoulder 2^m, Fig. 7, of the arm 2^a.

5 The arms have capacity for relative movement sufficient in extent to enable them to be separated far enough to receive the tension-pulley between them, with its journals in position to enter the holes or sockets of the 10 bearing-blocks, and to permit one of the said journals to be entered into the hole or socket of the bearing-block of one of the arms. The tension-pulley having been placed between the separated arms, and one 15 journal thereof having been inserted into one of the bearings, the arm 2^b may be swung toward the arm 2^a again, so that the other journal shall be received in the other bearing, and so that the ends of the bearing-blocks projecting from the pockets 2^d, 2^d, shall approach closely, or make contact with, 20 the shoulders 1^b, 1^b. Conversely, the arm 2^b may be swung apart from the arm 2^a sufficiently to permit of removal of the tension-pulley, or so as to withdraw one bearing 25 from the corresponding journal to permit the driving-band or tape to be applied to the tension-pulley, or to be disconnected therefrom and withdrawn. The same capacity 30 provides for inspection of the respective bearing-blocks, and for removal and replacement thereof. When the parts are in working relations with respect to one another, the journals and bearings are protected 35 from dust and flyings. The frictional engagement of the meeting-faces of the arms 2^a, 2^b, with each other, is sufficient to keep such arms in their closed working position with the tension-pulley between them, 40 and also to hold them in an opened condition as long as may be required, after they have been separated from each other. In the separated condition of the arms, the tension-pulley may be removed or replaced, 45 or the driving-band or tape may be placed on or taken off from the tension-pulley, or the required attention may be paid to the bearing-blocks, after which by moving the arms reversely into their normal relation the 50 parts may be restored to working condition.

It will be observed that the hole or opening 2^e in the upper end portion or arm 2^a of the bracket is a transverse one to enable the bracket to be attached to its support on 55 the spinning frame or other machine to which the device is to be applied. It will also be observed that the recesses or pockets 2^a at the end portions of the fixed and pivoted arms 2^a and 2^b are square or polygonal in 60 form so as to hold the bearing blocks 3 non-rotatively in place, the said recesses or pockets being closed at their outer sides to pre-

vent displacement of said bearing blocks when the pivoted arm of the bracket is swung down into operative position to retain the tension pulley in place. 65

The opposite faces 2ⁿ, 2ⁿ, Figs. 1 to 7, of the outer or upper end of the arm 2^a, are beveled or inclined so that when either of the said faces is placed in contact with a 70 surface of the supporting stand, and the bracket is bolted to the said stand, the bracket and tension-pulley shall occupy a slightly inclined position corresponding with the direction in which the band or tape 75 should travel. In a spinning-frame, the tension-pulleys are arranged right and left, as it may be termed. Consequently, the two opposite faces of the arm 2^a are inclined in opposite directions, as shown, in order that 80 a bracket and its tension-pulley placed at one point in the length of a spinning-frame may be made to incline transversely in one direction by causing one face 2ⁿ to rest against the proper surface of the support, 85 and a bracket and tension-pulley placed at an opposite point in the said length may be caused to incline transversely in the opposite direction by causing the other face 2ⁿ of 90 the bracket to make contact with a face of the support.

While I have been careful to describe fully and completely the construction which is shown in the drawings, I do not limit myself in all respects thereto in the case of 95 all embodiments of the principles of the invention.

Having thus explained the best form in which I have thus far contemplated embodying the invention, I claim as my invention:— 100

A tension-pulley supporting-bracket having a fixed arm and a pivoted arm both of which are provided with bearing blocks projecting inward beyond the pockets containing said bearing blocks, combined with a tension pulley having fixed journals fitting said blocks and provided with shoulders abutting against the inwardly projecting inner ends of said blocks to limit lateral movement 110 of the pulley; whereby the pivoted arm may be swung aside to unlock said pulley when it is desired to remove or replace the same or to permit the driving band or tape to be removed or replaced, and whereby also lateral 115 movements of the pulley in its bearings will be prevented.

In testimony whereof I affix my signature in presence of two witnesses.

CARL E. SPAULDING.
